(57) **CLAIM**

The ornamental design for a structure for a covered walkway or sidewalk shed, as shown and described.

DESCRIPTION

FIG. 1 is front perspective view of a structure for a covered walkway or sidewalk shed showing our new design; FIG. 2 is an enlarged view of detail 2 of FIG. 1; FIG. 3 is an exploded view of the detail view of FIG. 2 with additional broken lines showing the order of assembly; FIG. 4 is a left elevation view thereof, the right side being a mirror image thereof;

FIG. 5 is an enlarged view of detail 5 of FIG. 4;

FIG. 6 is a front elevation view of thereof, the rear being a mirror image thereof;

FIG. 7 is a top plan view thereof; and,

FIG. 8 is a bottom plan view thereof.

The ornamental design for the structure for a covered walkway or sidewalk shed that is claimed is shown in solid lines on the drawings: The evenly dashed broken lines illustrate portions of the structure for a covered walkway or sidewalk shed that form no part of the claimed design. The dot-dash broken lines of FIGS. 1-5 depict the boundaries of enlargement and form no part of the claimed design. The lightweight broken lines used in FIG. 3 show the order of assembly of the components in the exploded view and also form no part of the claimed design.
